RELEASE MECHANISM FOR BULKHEAD-DOORS AND THE LIKE.

1,088,272.

Specification of Letters Patent. Patented Feb. 24, 1914.

Application filed October 18, 1913. Serial No. 796,089.

To all whom it may concern:

Be it known that we, WILLIAM GREGORY GIBBONS and FREDERICK JOHN BLAKE, subjects of the King of Great Britain, and residing, respectively, at "Viewpark," Russell Place, Trinity, Edinburgh, in the county of Midlothian, Scotland, and "Beechcroft," Burgess street, Bassett, in the county of Hampshire, England, have invented new and useful Improvements in Release Mechanism for Bulkhead-Doors and the like, of which the following is a specification.

The invention relates to that type of bulkhead door mechanism in which the door is held open by a detent device which device is operated to release the door (allowing it to shut) by, for example, a float or by mechanism operated from a central station—on shipboard—the bridge.

The detent device may be of any convenient form—for example it may be in the form of a clutch connecting the door with its train of opening gearing in which train is a worm and wormwheel the absence of action through which causes the door to be held open as long as the clutch remains in engagement.

The invention has for its object to provide an improved relay device, that is to say a spring, weight, or equivalent powerful enough to withdraw the clutch or detent under all possible conditions, and operatively connected thereto. According to this invention this powerful relay which is in turn controlled by a detent is capable of being freed not only by the rising of a float, or by the comparatively small effort of an electro-magnetic or other bridge control but also by a hand control so that the relay is always the means by which the clutch or detent is operated. Combined with the relay is a resetting mechanism which enables the relay after use to be reset.

In previous arrangements in which the door was suspended by the detent device in the open position, the weight of the door assisted the relay device to assist the detent after the release of a catch by the action of a bilge float or bridge control. In the case of the release being effected by a person in the vicinity of the door the relay did not come into operation because means were pro-

vided for releasing the detent or door suspension device without releasing the relay. According to these improvements however, 55 the relay is released either by hand or by the action of a float, or by the bridge control and any one of these controls is capable of releasing the relay so that the latter may release the clutch or detent without interfering with either of the other controls.

According to a simple illustrative example, the clutch of ordinary jaw form—preferably having the jaws slightly angled for ease of engagement and disengagement 65 is held in gear by a spring or weight of sufficient effort to keep it so. It is operatively connected to a lever or plunger to which is applied the relay spring or equivalent which is of power sufficient to overcome the engaging spring and also throw out the clutch. This lever or plunger is in turn controlled by a simple detent catch operated by hand lever, float, or bridge mechanism. A lever socketed for the insertion of a pinch or 75 tommy-bar is provided to reset the relay device.

The apparatus may be used in combination with the hydraulic door-operating mechanism described in the specification of 80 our prior application for a patent, No. 789950 of 1913.

An illustrative example of the improved release mechanism is shown diagrammatically on the accompanying sheet of explanatory drawings.

As shown in the drawings the bulkhead door A is of usual form having on it a rack A¹ which engages a pinion A² on a shaft A³ operated through worm and wormwheel 90 gearing A⁴ by hand or power when it is desired to raise the door. On the wormwheel is one member A⁵ of a locking clutch the other member A⁶ of which is movable endwise on the shaft A³. When the two 95 parts A⁵, A⁶ of the clutch are engaged the door is held in its open position by the worm and wormwheel A⁴. On disengaging the movable part A⁶ of the clutch from the fixed part A⁵ the gearing is freed and the door 100 descends by its own weight to the closed position. Its descent may be controlled by cataract cylinders if desired, all in known manner.

As shown in the drawings the clutch locking device A^5 , A^6 of ordinary jaw form, preferably having the jaws slightly angled for ease of engagement and disengagement, 5 is held in gear by a spring B acting between a collar B^1 on the shaft A^3 and the movable member A^6 of the clutch. The clutch is operatively connected to a plunger C by means of a bell crank lever supported on a 10 bracket D , the one arm D^1 of the lever being connected to the movable member A^6 of the clutch and the other D^2 to a pivot D^3 in a slot C^1 in the plunger C . To the plunger C is applied a relay spring C^2 which 15 is of power sufficient to overcome the engaging spring B and also throw out the movable member A^6 of the clutch as hereinafter described. The plunger C is supported in brackets E , E^1 , E^2 and carries on its lower 20 end a link C^3 pivoted to it by a pin C^4 . This link C^3 is connected to one arm C^5 of a bell crank lever, centered on an extension on the fixed bracket E^2 the other arm C^6 of this lever being socketed to receive a pinch L for 25 a purpose hereinafter described.

In connection with the plunger C there is provided a pair of links F , F^1 hinged together at one end and pivoted at their opposite ends one to a pin F^2 on the bracket E^1 30 and the other to the pin C^4 . The lower link F^1 has on it a tail-piece F^3 on which bears a spring operated tappet F^4 tending to force the links to one side of the center line (the right hand) and against a cam G^1 formed 35 on the upper end of a handled lever G pivoted at G^2 on an extension E^3 of the bracket E^1 . When the parts are in the position shown, the links F , F^1 act as struts and prevent the power of the spring C^2 being 40 exerted to pull up the plunger C . When it is desired that the spring C^2 should operate the plunger C the handled lever G is rocked so as to cause the cam G^1 to throw the hinged ends of the links F , F^1 to the opposite side of the center line from that in 45 which they are shown. The spring C^2 is then free and the power in it acting between the bracket E and a collar C^6 on the upper end of the plunger C operates that plunger 50 as desired. In order to free the clutch on the rise of water in the ship's hold there is provided a float H connected to the pivot G^2 by means of links H^1 , H^2 . The link H^1 is also connected by means of a link H^3 to 55 the handled lever G so that when the float rises the handled lever G is rocked and the mechanism again operated as hereinbefore described. The link H^3 is slotted at H^4 to allow of the handled lever being rocked 60 without actuating the float device. Instead of the relay device being freed by either handled lever G or the float H , it may be freed by the comparatively small effort of an electro-magnetic or other bridge control.

During the operation of the relay device 65 to free the clutch, as hereinbefore described, the link C^3 has been raised and the bell crank lever C^5 , C^6 and pinch L rocked from the position shown in full lines to that of the dotted line L^1 . In order to reset the relay device the pinch L is pulled back to its first position, this pulls down the plunger C against the action of the spring C^2 and permits the spring actuated tappet F^4 to reset the links F , F^1 , in the position shown in the 70 drawing in which position they act as struts to lock the relay device in its acting position. When it is desired to release the clutch from a distance (such as the bridge) there is provided a small hydraulic cylinder J the plunger J^1 of which is operated as described in 75 the earlier specification hereinbefore referred to. This plunger carries links J^2 pivoted at J^3 to the arm D^2 of the bell crank lever. When the plunger J^1 rises, the links J^2 pull up the arm D^2 which then throws the movable member A^6 of the clutch out of engagement allowing the door to fall. During this movement the pivot D^3 travels 80 up the slot C^1 so that the clutch is released 85 without affecting the rest of the mechanism. Similarly the pivot J^3 works in slots J^4 in links J^2 so that when the relay device is worked the pivot J^3 travels up the slots J^4 without affecting the plunger J^1 of the hydraulic cylinder. 90

What we claim as our invention and desire to secure by Letters Patent of the United States is:—

1. In bulkhead door operating gear and in combination, door opening gear, a detent device therein adapted when engaged to prevent closure of the door, a spring relay device operatively connected with said detent, a detent catch normally preventing 100 said relay from operating, a hand lever operative to release said detent catch, a float also operative to release said detent catch, and resetting means operatively connected with said spring relay device substantially as described: 105

2. In bulkhead door operating gear and in combination, door opening gear, a clutch device therein adapted when engaged to prevent closure of the door, clutch closing 110 means normally operative to maintain said clutch in the closed condition, a spring loaded plunger, operative connection between said plunger and the disconnectible member of said clutch, a detent catch normally active to prevent operation of said spring plunger, releasing means in operative connection with said catch, and resetting means 115 operatively connected with said spring plunger substantially as set forth.

3. In bulkhead door operating gear and in combination, door opening gear, a clutch device therein adapted when engaged to

prevent closure of the door, clutch closing means normally operative to maintain said clutch in the closed condition, a spring loaded plunger operative connection between 5 said plunger and the disconnectible member of said clutch, toggle links connected between said plunger and a fixed framing member, spring means operative on said toggle to normally maintain the pivot center of said links about in alinement, an operatable cam adapted when turned to move the middle pivot of said toggle out of alinement, and a manually operated linkage con-

nected with said plunger and adapted to re-set the same substantially as set forth.
